UNITED STATES PATENT OFFICE

2,451,055

FUEL PUMP

Thomas Edward Beacham, London, England

Application May 9, 1944, Serial No. 534,750
In Great Britain March 8, 1943Section 1, Public Law 690, August 8, 1946
Patent expires March 8, 1963

7 Claims. (Cl. 103—5)

1

This invention relates to fuel pumps, and has particular reference to fuel pumps for supplying the fuel to internal combustion engines. Fuel pumps for this purpose are known, in which, in addition to the main pump, an impeller is provided for the purpose of creating a difference of pressure which bears a definite relationship to the speed of the pump and engine, which pressure operates through suitable control mechanism to regulate the flow of fuel from the main pump to the engine in such a way as to provide the required relationship between the quantity of fuel supplied and the engine speed.

The object of the invention is the provision of an improved layout of this character, and the invention consists broadly in the arrangement that the main pump (in conjunction with which the impeller is employed) takes the form of a gear pump. The invention also comprises the provision of a self-contained safety valve in the one casing with the pump.

In order that the invention may be the more clearly understood, a construction in accordance therewith will now be described, reference being made to the accompanying drawings, wherein:

Figure 1 is a side elevation of said construction, shown mainly in section on line I—I of Figure 2, a small part being in section on line I—I of Figure 3;

Figure 2 is an end elevation of the same looking from the left of Figure 1 with certain of the parts at the left hand end partly broken away;

Figure 3 is an end elevation of the same looking from the right of Figure 1, shown mostly in section on line III—III of Figure 1;

Figure 4 is a sectional plan taken on line IV—IV of Figure 1.

Referring to these drawings the construction comprises a main pump of the gear type for pumping the fuel to the engine (not shown) said pump comprising a single pair of gear wheels 1 and 2 and having inlet and outlet conduits 3 and 4 respectively. The gear wheel 1 is mounted on a main shaft 5 which is driven from the engine, and the gear wheel 2 is an idler gear which rotates on a short fixed shaft 6. In addition to the main pump 1, 2 I provide, on the shaft 5, an auxiliary impeller 7 acting to produce centrifugally a difference between the fluid pressures of two annular spaces 8 and 9, which difference is proportional to the square of the speed of the pump and therefore of the engine. The fluid pressures in said spaces 8 and 9 are applied, through respective conduits 10 and 11, to a suitable control mechanism (not shown) which responds to the

5 differences in said fluid pressures so as to regulate the flow of fuel from the main pump 1, 2 to the engine in such a way as to provide the required relationship between the quantity of fuel supplied and the engine speed. In practice the higher pressure space 8 is in full communication with the pressure side of the main pump 1, 2 and is accordingly at the pump pressure. The lower pressure space 9 is therefore at a pressure which 10 is lower than the pump pressure by an amount depending on the speed of the pump and engine. A slow reverse flow of fuel through the impeller is provided for by providing a restricted leakage path, as will hereinafter appear, from the lower 15 pressure region of said impeller to the low pressure side of the main pump. This leakage path comprises an orifice whose size can be adjusted to provide for any desired rate of leakage flow.

The auxiliary impeller 7 is of the type, as will 20 be clear from the drawing, comprising vanes in straight radial planes containing the axis. Said vanes rotate in an annular chamber which fits close to the side edges of the vanes. This annular chamber on one side (in practice the side away 25 from the gear pump 1, 2) communicates, as will be hereinafter explained, with the aforesaid two annular spaces 8 and 9. These spaces are, as shown, coplanar and concentric with the impeller, and the high pressure space 8 is at a radius about equal to that of the tips of the vanes, while the low pressure space 9 is at a radius rather greater than that of the roots of the vanes.

The pump 1, 2 is provided with a self-contained safety valve adapted, should the load become too high, to open and connect the pressure conduit 4 to the suction conduit 3. This safety valve, which is shown in Figure 4, comprises a disc-shaped valve element consisting of two parts 12 and 13 divided in the mid plane of the disc, which 35 valve element 12, 13 is biased by means of a spring 14 so that its part 12 seats on a circumferential ledge 15 on the inner periphery of a hole 16 which, on the seating side of said valve element 12, 13, is connected to the pressure conduit 4, and, on 40 the other side of said valve element 12, 13, is connected to the suction conduit 3. Thus when the pressure on the pressure side of the pump exceeds a given amount, the valve element 12, 13 is lifted from the circumferential ledge 15, and the liquid 45 flows from the pressure conduit 4 to the suction conduit 3.

In order that this valve shall not be influenced 50 by the pressure on the suction side of the pump, the valve element 12, 13 is connected by means of an axial strut 17, to a flexible diaphragm 18

which closes the hole 16 on the far side of the suction conduit 3. Thus the pressure on the suction side of the pump acts in opposite directions on the valve element 12, 13 and the diaphragm 18. The effective areas of said valve element and diaphragm on which this pressure acts are made equal, and thus the total effect upon the valve of the pressure of the suction side of the pump is zero. Beyond the diaphragm 18, a cap 19 is fitted on the end of said hole 16, which cap is fitted with a pipe connection 20. It is clear that by varying the pressure within the cap 19—that is the pressure on the outer side of the diaphragm 18, the pump pressure at which the valve 12, 13 will respond can be varied without any adjustment being made to the biasing spring 14. In practice a pipe from this cap 19 leads to the inlet of the engine supercharger, whose pressure may be above or below atmospheric. Thus the safety valve is automatically set to respond to a given pump pressure depending upon the pressure of the supercharger inlet.

In the construction of this safety valve, the circumferential ledge 15 is formed on an integral end piece 21 which fits accurately into the end of the hole 16 beyond the pressure conduit 4. The outer end of this end piece 21 is flanged as shown so as to form a complete closure for that end of the hole. The inner end of said end piece 21 extends to a point between the pressure conduit 4 and the suction conduit 3 and is hollowed and fits closely in said hole 16 as shown so as to form the said circumferential ledge. The intermediate part of said piece 21 is waisted as shown so as to form an annular space to which the pressure in the conduit 4 has access and is provided with holes 22 to admit said pressure to the appropriate face of the part 12 of the valve element 12, 13.

The part 12 of the valve element is formed with an axial projection 23 which engages slidably in a corresponding axial recess in the end piece 21. The axial strut 17 passes through a central hole in the part 13 of said valve element and, at its end, mates with an axial recess in said part 12 extending into the projection 23. The main biasing spring 14 is a coil spring in compression between the part 13 and a conical disc-shaped member 24 clamped across the end of the hole 16 just inside the diaphragm 18, said member 24 forming a bearing for the strut 17 and being provided with holes 25 by which access is given from the suction conduit 3 to said diaphragm. The strut 17 is formed with a flange 26 which is engaged by said part 13 to press the aforesaid end of said strut into the axial recess in the part 12, and the dimensions are such that the extremity of said strut engages the end of said axial recess so as to press said part 12 against the circumferential ledge 15 while maintaining the two parts 12 and 13 slightly spaced from each other. Holes 27 are provided in the part 12 which holes are normally kept closed by means of a closing disc 28 pressed down on to the high pressure side of said part 12 by means of a light coil spring 29 in compression between said closing disc and the end piece 21. It will thus be seen that, should the pump be inadvertently reversed so that the conduit 3 becomes the pressure conduit and the conduit 4 the suction conduit, the liquid can flow straight from the conduit 3, between the valve parts 13 and 12 and through the holes 27 to the conduit 4.

As will be seen the member 24 is clamped between the end of the hole 16 and the cap 19, the

diaphragm 17 being clamped between said member and cap.

The connections between the conduits 3 and 4 and the hole 16 are permanently established, as shown, but all the parts within said hole 16, from the end piece 21 to the cap 19, can be reversed with respect to said hole from end to end, so that the safety valve can still be used if it is desired to reverse the direction of operation of the pump and make the conduit 3 the pressure conduit and the conduit 4 the suction conduit.

In construction, the chamber for the pump gears 1 and 2 is constituted by a main block 30 and an end block 31 bolted with two adjacent faces, at right angles to the pump shaft, together, the face of the main block 30 being recessed to provide said pump chamber. The conduits 3 and 4 which pass to and from said chamber are formed wholly within said main block 30, and the hole 16 is accordingly also formed wholly within said main block. Assuming that the construction is orientated, as shown, with the shaft horizontal and the gear 1 vertically above the gear 2, said conduits 3 and 4 run parallel upwardly to the appropriate sides of the gear chamber, and said hole 16 is horizontal, running transversely through said main block 30 and cutting at one side into said conduits 3 and 4 as shown to establish communication with them.

Suitable recesses are also formed in the main block 30 and end block 31 to receive two ends of the fixed shaft 6 for the idler gear 2.

The pump shaft 5 passes through both blocks 30 and 31. Said shaft is provided with two plain journal bearings, one located between the gear 1 and the impeller 7, and the other located on the side of said gear 1 remote from said impeller. The first of these journal bearings consists of a steel sleeve 32 fixed on said shaft 5, running in a bronze bush 33 fixed in the main block 30. The other journal bearing is formed by an enlarged portion of the shaft 5 running in a bronze bush 34 fixed in the end block 31.

Said shaft 5 is also provided with a single end thrust bearing, since the load always acts in the direction from the impeller 7 to the gear 1. This end thrust bearing is constituted by an annular bearing element 35 fixed as shown to the end of the main block 30 remote from the gear, and engaged by a steel disc 36 mounted on the shaft at a position just beyond the said end of said main block. Said bearing element 35 may comprise bronze or graphite and the arrangement is such that the end thrust bearing keeps the two faces of the gear 1 just clear of the adjacent faces of the gear chamber.

The closely fitting chamber for the impeller 7, together with the two annular spaces 8 and 9 communicating with said chamber, are constituted in the following way:

A disc-shaped plate 37, which is dished as shown to accommodate the steel disc 36, is clamped between the end of the main block 30 and a cap-shaped part 38. The shaft 5 passes through the disc-shaped plate 37 and into the space formed between it and the cap-shaped part 38. The vanes of the impeller 7 are mounted on the shaft 5 close to the disc-shaped plate 37. The cap-shaped part 38 is formed with a hub 39 surrounding the end of the shaft on the other side of the vanes, and, around this hub, said cap-shaped part 38 is formed with an annular recess facing the vanes, in which is bolted, by means of bolts 40a, and aligned by means of a suitable regulator, a T section ring 40, arranged as shown

that its cross flange is close and parallel to the edges of the vanes and nearly cuts off the annular space from the vanes, and its centre flange divides said annular space into the two separate annular spaces 8 and 9. It will be seen that these two spaces 8 and 9 communicate with the closely fitting chamber in which the impeller rotates, respectively by way of a narrow annular clearance between the outer edge of the ring 40 and the inner periphery of the cap-shaped part 38 and by way of a narrow annular clearance between the inner edge of the ring 40 and the outer periphery of the hub 39. The aforesaid conduits 10 and 11 leading from said annular spaces 8 and 9 pass through the cap-shaped parts 38 and are adapted to be connected to suitable pipes. The said annular spaces 8 and 9 have the function of destroying the circumferential velocity of the liquid and preventing this from being converted into static head.

The shaft 5 at its end remote from the impeller 7 is provided with liquid seals to prevent leakage of liquid. Thus the end block 31 is hollowed, as shown, having a cylindrical axial recess in its end remote from the main block, into which recess the shaft 5 passes. The aforesaid bearing bush 34 is fixed in this recess at the end thereof nearest the main block 30. Secured in said recess next to said bearing bush 34 is a ring 41, which ring 41 is sealed with respect to the inner periphery of said cylindrical recess, by means of a ring of sealing material 42. A cylindrical part 43 is screwed into the end of said recess and sealed with respect to the inner periphery of said recess by means of an annular sealing disc 44. The extremity of the shaft proper 5 lies within said ring 41 and said shaft is coupled to a splined spigot 45 lying just outside the end block 31 by means of a so-called Oldham coupling which affords a hermetic seal both against said ring 41 and the cylindrical part 43. The splined spigot 45 is for coupling the shaft to the engine.

Thus said Oldham coupling comprises parts 46 and 47 coaxial with the shaft, the part 46 being adjacent the end of said shaft and having a diametrical tongue which engages a diametrical slot in the end of said shaft, and the part 47 being on the side of the part 46 remote from said shaft and having a diametrical tongue which engages with a diametrical slot in said part 46. The two diametrical slot and tongue connections are at right angles to each other as shown. The parts 46 and 47 are formed with respective flanges 48 and 49, and said parts are biased axially away from one another by means of a coil spring 50 in compression between said flanges and thereby said flanges are biased against respective sealing rings 51 and 52 mounted on the ring 41 and the cylindrical part 43 as will be clear from the drawings. As shown the spigot 45 is rigid on the part 47.

The fixed shaft 6 on which the idler gear rotates is provided, mid way along its bearing portion, with either a circumferential groove or a ring of circumferential holes 53 communicating with a hole 54 extending axially of said shaft to one end and leading to a passage 55 which communicates with the hole 16 at a point of the latter which is always connected to suction whichever the direction of operation of the pump. Thus fuel will leak from the gear chamber, through the clearance between each face of the idler gear 2 and the adjacent face of said gear chamber between said gear 2 and the fixed shaft 75

6 and through the passages 53, 54 and 55, to the suction side of the pump. Thus a flow of liquid is provided through the bearing of the gear 2 which ensures that it shall run with a reasonably small amount of wear.

As the hydraulic pressures at the two ends of the bearing bush 33 may be nearly equal at slow speeds, said bush mid way along its bearing portion, is preferably provided with a circumferential groove or a circumferential ring of holes 56 which communicate by way of a passage 57 with the said passage 55, so that a flow of fuel through the bearing 33 from both ends will take place. To enable the fuel to reach the left hand end of the bearing 33, the right hand face of the disc 36 is formed with shallow radial grooves. This also ensures lubrication of the end thrust bearing.

It will be seen by reference to Figures 1 and 3 that the low pressure side of the gear pump is in communication, by way of a conduit 58, with a transverse conduit 59 from which extends a longitudinal conduit 60. The conduit 60 is therefore at the pressure of the suction side of the pump. The aforesaid leakage path from the low pressure region of the impeller 7 to the suction side of the pump goes to this conduit 60 by way of a narrow annular clearance 61 at the inner edge of the dished plate 37 leading to the space 62 on the right hand side of said dished plate, from which space passages 63 and 64 lead to said conduit 60. An adjustable valve 65 regulates the rate of leakage through this path as will be clear from the drawing.

The trapped space on the right hand side of the bearing bush 34 is also connected to this conduit 60, by way of passages 66 and 67, so that undue pressure shall not be applied to the seals at 42 and 51.

It will be seen that a conduit 68 is provided leading from the conduit 59 to the high pressure side of the pump, but that this conduit 68 is closed by means of a valve 69 as shown. If however the direction of operation of the pump is to be reversed, this valve 69 will be exchanged with a plug 70, so that it will now close the conduit 58 and the conduit 68 will be open. Therefore, as will be clear from the drawing, the conduit 59 will still be connected to the suction side of the pump, now on the right of Figure 3, and cut off from the pressure side, now on the left.

Other constructional details are deemed sufficiently clear from the drawings.

What I claim and desire to secure by Letters

55 Patent is:

1. A fuel pump for an internal combustion engine comprising a gear pump adapted to be connected to and driven by the internal combustion engine at a speed corresponding to the engine speed and having inlet and outlet conduits adapted to be connected respectively to a fuel supply and said engine to deliver fuel from the former to the latter, an impeller coupled to the gear pump and driven therewith at a corresponding speed, a high pressure chamber connected with the discharge of said impeller, a low pressure chamber connected with the intake of the impeller, a pressure responsive means connected between said high and low pressure chambers and means associated with said pressure responsive means for varying the flow of fuel from said gear pump to the engine.

2. A fuel pump as defined in claim 1 in which the high pressure chamber is connected with the pressure side of the gear pump.

3. A fuel pump as defined in claim 1 in which the high pressure chamber is in full communication with the high pressure side of the gear pump and the low pressure chamber communicates with the low pressure side of the gear pump through a leakage path.

4. A fuel pump as defined in claim 1 in which the high pressure chamber is in full communication with the high pressure side of the gear pump and the low pressure chamber communicates with the low pressure side of the gear pump through an adjustable leakage path.

5. A fuel pump as defined in claim 1 in which the impeller comprises radial vanes enclosed within an annular impeller chamber, the high pressure chamber is an annular chamber coaxial with the impeller chamber and communicates therewith adjacent the tips of the radial vanes and the low pressure chamber is an annular chamber coaxial with the impeller chamber and communicates therewith adjacent the roots of the radial vanes.

6. A fuel pump as defined in claim 1 in which the impeller comprises radial vanes enclosed within an annular impeller chamber and the high pressure and low pressure chambers are annular chambers coaxial with said annular impeller chamber, said impeller chamber and said annular high and low pressure chambers being separated from each other by an annular member of T-shaped cross section having its cross flange adjacent to the radial vanes and its center flange positioned between the high pressure chamber

and the low pressure chamber, there being clearances between the inner and outer edges of said cross flange and the adjacent walls of said chambers providing communication between the impeller chamber and said high and low pressure chambers.

7. A fuel pump as defined in claim 1 comprising a safety valve connected between said inlet and outlet conduits, said safety valve comprising a symmetrical cylindrical chamber, closure means for both ends of said cylindrical chamber and valve means and valve biasing means supported between said closure means, said closure means and the valve and valve biasing means being reversible with respect to said cylindrical chamber.
